UNITED STATES PATENT OFFICE.

CHARLES L. GOODRUM, OF ATHENS, GEORGIA, ASSIGNOR, BY MESNE ASSIGNMENTS, TO
WESTERN ELECTRIC COMPANY, OF NEW YORK, N. Y., A CORPORATION OF ILLINOIS.

AUTOMATIC TELEPHONY.

1,147,716.

Specification of Letters Patent. Patented July 27, 1915.

Application filed June 18, 1912. Serial No. 704,274.

To all whom it may concern:

Be it known that I, CHARLES L. GOODRUM, a citizen of the United States, residing at Athens, in the county of Clark and State 5 of Georgia, have invented certain new and useful Improvements in Automatic Telephony, of which the following is a specification:

My invention relates to improvements in 10 automatic telephony and particularly to the arrangement of automatic switches and the circuits for the same to effect interconnection between subscribers at an exchange without the use of operators.

One of the objects of my invention is to 15 provide means for reducing the number of contacts and simplify the switches commonly known as the selector switches and in carrying out this invention I employ the flat 20 or one-movement switches of the Lattig and Goodrum type in which contacts arranged in permanent banks are adapted to be successively engaged by wipers rotated across them, as distinguished from those systems 25 having two-movement, or what is known as up-and-around, switches for first picking out a group and then a contact in the group, such as the so-called Strowger system.

One of the principal features of my invention is the employment of intermediate 30 testing or finder switches which are automatically operated to find a subscriber's line or a trunk which has been connected by a selector switch operated by the usual calling 35 device at the subscriber's station to a calling line.

In the early history of the so-called Lattig and Goodrum system, finder switches were 40 employed to find the subscriber's line and automatically connect them to a first selector, thus dispensing with the individual first selector of the automatic system then in use, the subsequent finding of groups and idle trunks in these groups leading to other 45 switches being accomplished in the then well known way. In such cases these selectors would select a group by impulses from the operator's calling device and then automatically find an idle trunk in this group. 50 In the present system I employ the same finder system for finding the line and connecting it to an idle selector from the banks of which trunks lead to different groups of other selector or connector switches depending 55 on the size of the exchange. Interme-

diate finders are then employed at each group for finding the trunk and the selector switch which has been connected to the line; these finders are tied to the next selector or connector switch as the case may be, and, 60 if a selector switch, it is again operated to find a trunk leading to another group which would be again picked out or found by another intermediate finder or back testing switch for the group selected and so on 65 through a third selector or connector, the last intermediate finder being tied to the connector switch in the group desired which is then operated in the usual way to select the called line.

In the accompanying drawings: Figure 1 is a diagrammatic view showing a subscriber's station and a finder switch for selecting the calling line and connecting it to the first selector switch, there being also 70 shown in this figure a distributing switch for distributing calls to the different finder switches, this distributing switch being the subject matter of other applications and not a part of this invention. Fig. 2 is a dia- 75 grammatic view of the first selector switch and the intermediate finder or back test switch for finding the trunk selected by the selector switch; this first selector switch being tied to the line finding switch of Fig. 80 1. Fig. 3 is a diagrammatic view of the intermediate or back test finder for finding the trunk selected by the second selector and also the connections to the called line. 85

It may be noted that the drawings by being placed together with the top of the first sheet adjacent to the bottom of the next and so on will show the connections extending through and between the various switches.

Like parts are represented by similar characters of references in the several views.

Referring now to Fig. 1, the subscriber's station A is equipped with the usual apparatus for common battery installation consisting of a transmitter, 1, receiver 2, hook-switch 3, ringer 4, condenser 5, and a sending device 6, for transmitting impulses for operating the switches at the exchange. The line and mate conductors a and a' from each subscriber's station terminate in contacts a^2 and a^3 in the bank of the line finding switch F; these line and mate conductors being multiplied to other finder switches in the usual way. The line and mate conductors a and a' are normally connected to a line 105 110

relay α^4 , through the circuit breakers α^5 and α^6 of the cut-off relay B, the circuit for this relay α^4 being from the conductor a , by wire 7, spring α^5 , contact 8, wire 9, relay α^4 , wire 10, battery 11, conductor 12, contact 13, spring α^6 , wire 14, to conductor a^1 so that closing the subscriber's line at the hook-switch 3 operates the line relay α^4 . Relay α^4 when magnetized operates grounded spring α^7 and causes it to move away from the contact 15 and engage contact 16. Contact 15 is connected by line 17 to a bank contact 18 in the finder switch, while contact 16 is connected by wire 19 through the 15 distributing switch d and wire 19^a to the starting circuit of line finder switch F. For the purpose of this invention the distributor switch may be omitted and the wire 19 may be considered as connected directly to the 20 wire 19^a as the distributor switch simply distributes calls to different finder switches of which F is one, the result being that when the line relay α^4 is operated the switch F is started to find the operated line as follows: The wire 19^a connects with off-normal spring c of the finder switch F which normally engages contact 20 connected by wire 21, contact 22 and spring 23 to the motor magnet d to battery and ground. 25 The motor magnet d operates the switch and causes its wipers to traverse the bank contacts. The initial energizing of the motor magnet d through the off-normal spring c causes the switch to make one step 30 when the circuit is opened at contact 22 by the attraction of the spring 23 on the motor magnet d , the operating mechanism of the switch being such that it makes one step each time the motor magnet is energized and deenergized in a well known way. As soon 35 as the finder switch takes one step the off-normal spring c moves from contact 20 into engagement with contact 24 so that the starting circuit through wire 19^a is opened 40 and the impulses necessary to continue the operation of the finder switch must come from another source. The first current impulse which passes over the starter wire and through wire 21 also passes over the branch wire 25 to a controlling relay e and thence by wire 26 to battery and ground. This 45 energizes the controlling relay e and operates springs e^1 and e^2 and e^3 . The spring e^3 is thus brought into engagement with contact 27 connected to the line 25 and line 25 is thus connected through spring e^3 to line 28 which leads to the wiper 29 of the finder switch F. This wiper 29 is adapted to engage the contacts in the lower row or bank 50 in which is located the contact 18 connected by wire 17 to the contact 15 opened by the energizing of the line wire a^4 . The contacts in this row or bank are therefore normally grounded at contact 15 through the 55 springs α^7 of the various line relays α^4 so

that if the wiper 29 on the first switch movement falls on a grounded contact current is supplied to the motor magnet from battery and ground over the following circuit: From grounded battery, motor magnet d , spring 70 23, contact 22, wire 25, contact 27, spring e^3 , wire 28, wiper 29, contact 18, wire 17, contact 15, spring α^7 to ground. As soon as the wiper falls on the contact 18 of the line which has been operated, there being no ground on this contact, the line branch being open at contact 15, the finder switch F stops with the wipers α^8 and α^9 resting on the contacts a^2 and a^3 of the line and mate wires a and a^1 which constitute the talking circuit. 75 The switch wipers α^8 and α^9 are connected by line wires a^{10} and a^{11} directly to the corresponding wipers of the first selector switch S. The dropping back of the relay E causes the spring e^2 to engage grounded back 80 contact 30. Spring e^2 is connected by wire 31 to switch wiper 32 which engages the third row of bank contacts 33 and these contacts are connected by branch circuits 34 to the cut-off relays of the respective lines so 85 that when the wiper 32 rests on one of the contacts 33 which are connected by branch lines 34 to the cut-off relays b of the respective lines and thence to battery and ground with the relay e deenergized, the 90 cut-off relay b is operated over the following circuit: Grounded battery, relay b , wire 34, contact 33, switch wiper 32, wire 31, spring e^2 and grounded contact 30. This energizes the relay b which thus attracts spring a^5 and 95 a^6 and breaks the circuit for the line relay α^4 at contacts 8 and 13. When the finder switch F has stopped on the line wires of the calling party and these line wires are thus 100 extended to the first selector switch, the first selector switch is placed in condition to be 105 operated by the controlling relay S^1 . This is accomplished as follows: The off-normal spring c of the finder switch engaging contact 24 at the first step of said switch, places 110 ground on the said spring through wire 35 to ground. A branch wire 36 leads from the off-normal spring c to contact 37 which is a back contact for the spring e^1 of controlling relay e and this spring e^1 is connected by wire 38, contact 39, spring f^{11} of 115 relay f^{10} and wire 40 to spring 42 (in the selector switch S) normally engaging back contact 43 connected by wire 44 to the controlling relay S^1 of the selector switch S 120 so that as soon as the finder switch F stops and the controlling relay e (in the finder switch, Fig. 1) is deenergized the controlling relay S^1 (Fig. 2) is operated over the 125 circuit just described from grounded off-normal spring c to the said relay and then by wires 45 and 46, battery and ground. The energizing of the relay S^1 closes the armature springs 47 and 48 to contacts 49 and 50 which are tapped onto the extensions 130

- a^{10} and a^{11} of the line and mate wires a and a^1 , these lines a^{10} and a^{11} being connected to the switch wipers a^{12} and a^{13} of the selector switch. The springs 47 and 48 being thus connected to the line and mate wires extended, bring these line and mate wires into the operating circuits of the switch so that the switch can be operated by the impulse sender at the subscriber's station and stepped 5 around to the desired group of contacts. As soon as the switch stops upon the group terminals a second or intermediate finder or back test switch F^1 is started which finds the trunks leading from the terminals selected. 10 This is accomplished as follows: The starter wire 51^a of the finder switch F^1 is connected through the distributor switch D^1 as before described, to wire 51 which leads to the terminal contact 52 on the bottom row of terminals 15 in the selector switch bank, which is adapted to be engaged by wiper 53 as the switch advances and which wiper will, in the operation of the switch, be grounded so that a starting impulse is given to the intermediate finder or test switch F^1 to cause it 20 to start and find the trunks a^{14} and a^{15} selected by the selector switch. The main wipers a^{16} and a^{17} of this intermediate finder or back test switch are connected by wires 25 a^{18} and a^{19} to the main selecting wipers of the connector switch C shown in Fig. 3, so that after the intermediate finder or back test switch F^1 has found the trunk selected by the selector switch S , the connector switch 30 will be connected directly to the calling subscriber's station and the connection to the called subscriber will be made by the operation of the impulse sending device in the usual way. 35 I have shown only one selector switch and consequently one intermediate finder. If other selectors are necessary owing to the size of the exchange they would be connected up in a similar way. The intermediate or 40 second finder switch F^1 would be connected to the second selector which would be operated from the impulse sending device at the calling subscriber's station as in the case of the first selector and the third finder would 45 be employed to find the group trunks selected by the second selector and if necessary this finder switch would be connected to a third selector and an intermediate finder and thence to the connector, the system being extended as is necessary to accommodate 50 the ultimate size of the exchange. 55 The particular form of the selector and connector switches is unimportant as various forms of switches well known may be 60 used for making the group selection from impulses from the subscriber's sending device but I will describe briefly the operation of the switches as I have illustrated them. 65 Taking up the selector switch the operation of the controlling relay S^1 , operating
- its armature springs 47 and 48 energizes the operating relay S^2 over the following circuit: grounded spring 47, contact 49, line wire a^{11} , mate a^{10} , line switch F , line and mate a and a^1 , closed sub-station, contact 50, 70 spring 48, wire 54, operating relay S^2 , wires 55 and 56 to battery and ground. The relay S^2 when energized attracts springs 57 and 58. Spring 58 is grounded and when attracted engages contact 59 which is connected by wire 60 to slow relay S^3 thence by wires 61 and 56 to battery and ground; relay S^3 is thus energized. Relay S^4 is also operated when the lines are closed through from the selector switch S as follows: Spring 47, 80 of relay S^1 is grounded and when relay S^1 is energized this ground is from contact 49 tapped onto line wire a^{11} , which is connected to wiper a^{12} . Wiper a^{12} normally rests on a contact 62 which is connected by wire 63 to 85 relay S^4 thence by wire 64 to front contact 65 and armature spring 66 on relay S^3 , this armature spring being connected by wire 67 to wire 56 and to battery and ground, so that the closing of relay S^1 followed by the energizing of relays S^2 and S^3 will also energize relay S^4 . These four relays S^1 , S^2 , S^3 and S^4 will all be energized as the result of the finding of the line by the finder switch and the transfer of the talking circuit to the wipers 90 of the selector switch S . Relays S^3 and S^4 are slow relays, while relay S^2 is a normal relay and will respond to impulses of current coming thereto through the contacts 50 and 49 tapped onto the line and mate wires 100 a^{10} and a^{11} . Spring 58 of relay S^2 has a back contact 68, and this is connected by wire 69 to motor magnet S^5 , the other end of whose coil is connected by wire 70 to contact 71 of relay S^4 whose armature spring 72 engages 105 this contact, this armature spring being in turn connected by wire 73 to wire 64 which leads to contact 65 on relay S^3 . The result of this is that with relays S^3 and S^4 energized a vibration of the spring 58 caused by 110 the energizing and deenergizing of relay S^2 by impulses in the line wires will cause these impulses to be transferred to the motor magnet S^5 over the circuit last described, these vibrations serving also to alternately open 115 and close in fairly rapid succession the circuit of the slow relay S^3 and cause said relay to hold up as long as the impulses are passing through it, thus keeping the circuit of the motor magnet closed at contact 65. It 120 will thus be seen that the impulses coming from the subscriber's sending device will cause the relay S^2 to be energized and deenergized which will in turn energize and deenergize the motor magnet S^5 and cause 125 the switch to be advanced one step at each impulse. The first impulse of the switch moves the wiper a^{12} off the contact 62 and the circuit for the relay S^4 would thus be broken at this point, but when relay S^4 was 130

energized it pulled up an armature spring 74 against contact 75 which is connected by wire 76 to back contact on spring 57 of relay S², which spring is connected by wire 78 to 5 wire 63 leading to the relay S⁴ so that as the relay S² (which I call the operating relay) is operated in response to the impulse sending device, impulses will be given to the relay S⁴ over the circuit last described and 10 by wire 64, contact 65, spring 66, wires 67 and 56 to battery and ground; this relay being a slow relay will be held up so long as these impulses continue. After the first step 15 of the switch therefore the slow relays S³ and S⁴ and relay S⁵ are controlled by the operating relay S². The motor magnet being vibrated in unison with the operating relay and the slow relay S³ getting impulses of current from the forward contact and the 20 relay S⁴ getting impulses of current from a back contact with the circuit for the motor magnet going through contacts on both of these slow relays, the switch wipers are thus operated in response to the impulses until 25 the wipers reach the desired group of contacts. As soon as the impulses cease, the lines still being closed at the subscriber's station with the telephone off the hook, the relay S² will remain energized. This will 30 break the circuit of relay S⁴ at contact 57 and relay S⁴ will become deenergized and will break the circuit for the motor magnet at front contact 75 of the relay S⁴ and inasmuch as the circuit for the relay S⁴ is 35 through one of its own contacts (after the switch has made one step) this motor magnet circuit can not again be established until the switch wipers have returned to normal. The dropping back and deenergizing of the 40 relay S⁴ also closes the starting circuit 51 and 51^a for the finder switch F¹. The wiper 53 having stopped on the contact 52, this wiper 53 is connected by wire 79, spring 80, contact 81, wire 82, back contact 83 (on 45 relay S⁴), wire 84, contact 85, spring 86, (on relay S³) to ground. This gives the intermediate finder F¹ an impulse in the manner substantially as described for finder switch F. This finishes the operation of the selector 50 switch until after the intermediate or back finder has found the trunk which has been selected by its selector switch. In this connection the wipers a¹² and a¹³ extend the main lines and talking circuit as before described. The wiper 53 gives the starting impulse to the back finder switch F¹ and the other wiper 88 rests on the contact 89 which is connected by wire 90 to the contact 91 on the back finder switch. This wiper 88 of the 55 selector switch is connected by wire 92 to relay S⁷ and through relay S⁷, wire 93 to relay S⁶ and thence by wire 94, contact 95, spring 96, wire 97 to battery and ground. This places grounded battery on the wiper 60 65 88. The relay S⁶ is, however, normally

shunted over wire 98, branching from wire 94 to contact 99, normally engaged by spring 100 on relay S⁷ which spring is connected to wire 93. The relay S⁷ is a low resistance relay, while relay S⁶ is a high resistance 70 relay for the purpose hereinafter described. The intermediate finder switch F¹ having been thus started by an impulse over the starter wire will continue its operation until its test wiper falls on test contact 91 at 75 which time the main wipers will rest on terminals of the selected trunk groups a¹⁴ and a¹⁵.

The operation of the intermediate finder F¹ is somewhat different from the first finder 30 and I will now proceed to describe it.

The starter wire 51 is connected to the off normal spring c¹ which is connected by wire 101 to the motor magnet f, thence by wire 102, contact 103, spring 104 on the motor 85 magnet, wires 105 and 106, spring 107, back contact 108 to battery and ground so that the motor magnet will be operated. Relay f¹ is in multiple with the motor magnet f over the branch wires 109 and 110, leading 90 respectively from the wires 101 and 105, so that it is energized and will be energized simultaneously with the motor magnet. The motor magnet, however, when energized breaks its own circuit at contact 104 but 95 relay f¹ will be held energized by a holding circuit formed in part by its own spring 111, which is grounded through wire 112, engaging contact 113 which is connected by wire 114 to wire 109, so that when this relay is 100 energized its spring 111 closes the holding circuit just described by engaging contact 113. The motor magnet being in multiple with the relay f¹, its circuit is also closed through this branch line 114, contact 113, 105 spring 111, wire 112 to ground and the motor magnet will continue to vibrate, breaking its own circuit and reestablishing it and thus the switch will continue to step until the motor magnet circuit is broken at contact 110 108 which occurs when the relay f² is energized, and this relay f² is energized when the wiper 116 drops onto contact 91, which is supplied with potential over the wire 90 as before described. Wiper 116 is connected 115 by wires 117 and 118 to the relay f² and to ground hence the relay f² is energized the moment the wiper engages the terminal 91 and the switch is stopped by the breaking of the motor magnet circuit. This also breaks 120 the circuit of the relay f¹ which drops back. The relay f¹ in dropping back allows the spring 111 to engage the back contact 119 which is also connected to wire 117 thus putting ground on the wiper 116 which maintains the high resistance relay S⁶ energized and also prevents any other switch 125 from stopping on its contact. The relay f¹ dropping back also breaks its own circuit and cannot be pulled up again until the 130

switch wipers have returned to normal and the off-normal spring c^1 brought to its normal position. The line and mate wires a^{18} and a^{19} are thus connected through wire a^{20} and a^{21} to the connector switch. These lines are preferably held open by relay f^3 whose springs 120 and 121 serve as circuit breakers in the lines a^{18} and a^{19} . This relay is operated by the energizing of relay f^1 from 5 grounded contact 122, spring 123, wire 124, to relay f^3 , battery and ground and when f^1 is deenergized, f^3 is also deenergized. The relay f^3 is preferably a slow relay so that these contacts are held open for a short time 10 after the relay loses its current. This is especially desirable as this relay is also operated when the switch is released. The relay f^3 also carries a spring 125 in the switching circuit for the connector switch 15 which extends from the off-normal spring c^1 to spring 127, contact 128 to spring 125, thence by wire 129 to the connector switch, and this switching circuit is also closed at spring 125 when relay f^3 is deenergized.

20 I have now described how the intermediate or back test switch F^1 has found the trunk group selected by the selector switch S in response to impulses from the calling subscriber's sending device. The next operation is to select the line by similar impulses from the sending device and this involves the operation of the connector switch, any well known form of which might be used. The operation of the one which I have 25 illustrated is as follows: The line and mate wires a^{20} and a^{21} terminate in an operating relay o preferably tandem wound, the lines being preferably connected to the different windings with battery interposed. The 30 switching wire 129 (from switch F^1) is connected to switching relay o^1 and thence by wire 130 to battery and ground. Both operating and switching relays are thus energized at the final action of the intermediate finder F^1 . The energizing of the operating relay o closes the grounded spring 35 131 against contact 132 which is connected by wire 133 to relay o^2 thence to battery and ground. It thus energizes relay o^2 which is a slow relay. This pulls up the armature spring 134, to contact 135 which is connected by wire 136 to relay o^3 which is connected by wire 137 to contact 138, normally engaged by off-normal spring c^2 , thence to ground so 40 50 that relay o^3 is thus energized, this also being a slow relay. o^3 in pulling up operates the armature spring 139 against contact 140 which is connected by wire 141 to relay o^4 , also a slow relay, which in turn is connected by wire 142 to contact 143 on relay o^2 . This contact has been engaged by grounded spring 45 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960

tor magnet o^5 , thence by wire 146, contact 147, spring 148, wire 149 to wire 142, contact 143, grounded spring 144, the circuit being open at contact 147 by the energizing of the operating relay o . The switch is now 70 in condition to be stepped around which is done by successive break-and-make contacts of the sending device at the calling subscriber's station. At each break in the circuit, the operating relay o is deenergized and the motor magnet circuit is closed at contact 147 by spring 148 which energizes the motor magnet o^5 and it will be immediately broken by the energizing of the operating relay o . This continues as many times as 75 there are impulses transmitted by the sending device and steps the switch around to the terminals of the called subscriber's line. It will be remembered that the preliminary energizing of the relay o^3 was through wire 137 and contact 138, off-normal spring c^2 to ground. This ground will be removed at the first step of the switch and the relay o^3 is held up by a circuit composed of wire 150, (which is a branch from wire 137), contact 90 151, spring 152, wire 153, spring 154, contact 155, to wire 142 and thence to contact 143, and spring 144 to ground. The spring 154 will be vibrated in unison with the spring 148 which opens and closes the motor magnet circuit and this will furnish impulses to the relay o^3 which, being a slow relay, will remain energized when the impulses cease, so that the circuit for the motor magnet will be thus held closed at contact 140 so long 95 as the impulses continue in fairly rapid succession, but this circuit will be opened so soon as the impulses cease. It will be remembered that relay o^3 controls the circuit for the relay o^4 at spring 139 and contact 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960

The line and mate wires a^{20} and a^{21} are connected through branches a^{22} and a^{23} and condensers c^{22} and c^{23} , wires a^{24} and a^{25} , to contacts 156 and 157. These contacts are adapted to be engaged by armature springs 158 and 159 on the relay o^6 and these springs 110 are in turn connected by wires a^{26} and a^{27} to the switch wipers a^{28} and a^{29} , which represent the extension of the line and mate wires and which will contact with the terminals of the called subscriber's line, the 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960

be momentarily held up after the switch has found the line, due to the fact that the relay o^4 is a slow relay and is being held up by relay o^3 which is also slow to release. Spring 5 162 therefore will remain momentarily engaged with contact 166 which is connected by wire 167 through spring 139^a on relay o^3 , wire 168, to relay o^7 battery and ground, so that in the event that the called party were 10 busy the switch wiper 160 would find ground over the circuits heretofore described and thus relay o^7 would be operated. As soon as relay o^7 is energized it locks itself up through wire 169, contact 170, spring 171, 15 contact 143, spring 144 to ground. Inasmuch as this circuit is closed at contact 143 by relay o^2 and relay o^2 is energized by the energization of the operating relay o , the relay o^7 , if operated, would be held energized 20 until the calling party hangs up and energizes the operating relay o . Relay o^7 is also provided with armature spring 172 which is connected by wire 173 to the busy tone T and this spring 172 is, when the relay 25 is energized, in engagement with the contact 173 connected by wire 174 to one side of the line a^{24} so that the busy tone is thus transmitted back in the usual way to the calling subscriber and notifies him that the line 30 called is busy. Relay o^8 is the ringing relay and in case the called line is not busy and relay o^7 is not therefore energized ringing relay o^8 will be energized by the dropping back or deenergizing of relay o^3 , this 35 being accomplished through the circuit beginning with battery and ground (at relay o^8) spring 139, contact 175, wire 176, relay o^8 , wire 177, spring 178 on the switching relay o^1 , contact 179, wire 180, contact 181 40 (on relay o^7), spring 171, contact 143, spring 144 to ground. The energizing of relay o^8 closes an interrupted circuit through relay o^6 as follows: from grounded battery, interrupter I, wire 182, spring 183, contact 184, 45 wire 185, spring 186, (on relay o^8), wire 187 to relay o^6 and ground. The relay o^6 it will be remembered controls the circuit breakers 158 and 159 in the line circuit passing through the wipers a^{28} and a^{29} and these 50 circuit closers will be periodically opened and closed by the interrupted battery circuit just described and put interrupted ringing current on the line wires through the following circuit: from ground at generator g , wire 188, spring 189, contact 190, wire 191, back contact 159, thence to wire a^{26} and wiper a^{28} to the calling subscriber and back over wiper a^{29} , wire a^{27} , to spring 158, back 55 contact of said spring, wire 192, contact 193 60 (of relay o^8), spring 194 and to ground thus periodically operating the called subscriber's ringer. If the called subscriber should answer by removing his telephone from the switch hook, and thus closing the line wire 65 a^{26} and a^{27} , the relay o^{10} would be operated

by the springs 158 and 159 closing on contact 156 and 157 (from the interrupted battery) thus closing the circuit through those contacts and wires a^{24} and a^{25} to relay o^{10} and included battery. The relay o^{10} being energized energizes relay o^9 by operating spring 195 against grounded contact 196, the said spring being connected by wire 197 to relay o^9 battery and ground. Relay o^9 is thus energized and its armature spring 186 is engaged with 75 contact 198 from battery to ground and thus breaks the interrupted battery circuit for relay o^6 (through the springs of relay o^8) heretofore described and energizes said relay o^6 through the circuit last described. The 80 relay o^6 is thus continuously energized so long as o^9 is held up and the talking circuit is completed through the condensers c^{22} and c^{23} over the line and mate wires extended as heretofore described. It will be understood 85 that the generators and tone devices are of the usual type continuously operated from some suitable source of power. This completes the connection of the calling line to a called line by the aid of the one movement 90 switches and the use of the back test or finding system consisting as heretofore described of first finding the subscriber's line and then by an impulse sender connecting it to a group trunk then finding the group 95 trunk and by an impulse sender connecting it to another group trunk or selector and then finding the proper group or line in the selector or connector as the case may be. When the conversation is completed and 100 the subscribers hang up their receivers, the switches will be released in pairs. Thus, the connector and its associated finder switch will be released first and as soon as they start to return to normal a circuit is opened, 105 which initiates the first operation in the release of the selector switch and its associated finder. In this system the release of the switches is under the control of either the calling party or the called party and we 110 will assume therefore that the calling party having finished his conversation has hung up his receiver for the purpose of release. In hanging up he opens his line circuit at the hook-switch which breaks the circuit for 115 the operating relay o of the connector switch. This in turn breaks the circuit for relay o^2 . The release magnet of the connector switch is shown at R^1 and its circuit may be traced from ground (at switching relay o^1), spring r^1 , wire r^2 , spring and contact r^3 (on relay o^2), 120 wires r^4 and r^5 to release magnet R^1 thence by wire r^6 to the intermediate finder switch F^1 (Fig. 2) contact and spring r^7 on relay f^4 to battery and ground. This energizes the 125 connector release magnet R^1 but this is only the preliminary operation, the switch being released when the magnet is again deenergized. The energizing of release magnet R^1 closes a circuit from grounded spring 124 130

(at relay o^2) through wire r^8 , contact r^9 , spring r^{10} , wire r^{11} , to intermediate finder switch F^1 and the release magnet rf thereof (see Fig. 2). The energizing of the release magnet rf makes the preliminary step for the release of the intermediate finder switch and also closes a circuit from ground (at relay f^2) through wire r^{12} , spring r^{13} , (on release magnet rf), contact r^{14} , wire r^{15} to relay f^4 , which energizes said relay f^4 and breaks the circuit at r^6 of release magnet R^1 through wire r^6 and this deenergizes the release magnet R^1 and releases the connector switch. The deenergizing of the release magnet R^1 also opens the circuit at r^9 for the release magnet rf of the intermediate finder switch F^1 and causes it to release. The energizing of the relay f^4 also opened the circuit of the line wires (in switch F^1) so that the wipers are temporarily disconnected in returning to their normal position. Release magnet rf being deenergized also breaks the circuit for relay f^4 as described and its spring also returns to normal.

It will be remembered that in the selector switch S relays s^6 and s^7 were held up by a circuit through the third wipers 88 and 116 in the respective switches F^1 and S . The circuit extends from ground at relay f^1 (in switch F^1) through the two relays s^7 and s^6 to battery and ground at relay s^8 (in switch S) passing through back contact 119 on relay f^1 (switch F^1) and back contact 94 on relay s^4 , (switch S). When the switch wipers of F^1 therefore return to normal, this circuit is opened and relays s^6 and s^7 are deenergized and close the release circuit for the selector switch S as follows: from ground at the off-normal spring c^3 of the selector switch S through wire r^{16} , back contact and spring r^{17} of relay s^6 , back contact and spring r^{18} of relay s^1 , back contact and spring r^{19} of relay s^8 , wire r^{20} to release relay R (switch S) thence by wire r^{21} to back contact and spring r^{22} on relay f^{10} of the line finding switch F to battery and ground. This energizes the release magnet R of the selector switch S as the preliminary step to release the selector switch, and the energizing of the release magnet fr of the line finding switch of Fig. 1 as follows: from grounded spring 58 of relay s^2 , back contact 68, wire r^{23} , contact r^{24} , armature spring r^{25} of release magnet R , wire r^{26} , to release magnet fr , line finder switch thence by wire r^{27} back to the selector switch S , back contact r^{28} and spring 66 of relay s^3 , wire 67 to battery and ground. This energizes the release magnet fr of the line finder switch F allowing it to make a preliminary step for releasing this switch. In pulling up, the release magnet, fr closes the circuit for the relay f^{10} in the line finding switch F from grounded spring r^{29} , contact r^{30} , wire r^{31} , relay f^{10} , to

battery and ground. The energizing of relay f^{10} on the closing of this circuit opens the circuit for release magnet R of the selector switch at spring and back contact r^{22} of this relay. This causes the release of the selector switch S and also the deenergizing of this release magnet R opens the circuit for the release magnet fr of the finder switch F at contact r^{24} in the selector switch S (Fig. 2). This deenergizes the release magnet fr which in turn opens the circuit for the relay f^{10} which in dropping back restores everything to normal. If the called party should hang up first he may also release the switches as follows: A branch circuit for the release magnet R^1 of the connector switch extends from wire r^5 by wire r^{32} , to spring and contact r^{33} on relay o^{10} , wire r^{34} , spring and front contact r^{35} on relay o^9 , wire r^{36} to spring and back contact r^{37} on relay o^4 to ground. When the called party hangs up first, relay o^{10} , being in the line circuit will be released and spring r^3 will drop back and close the release circuit just described through the release magnet R^1 back to the other switches as before described and at the same time the circuit for relay o^9 will be opened at contact 196 and o^9 being a slow relay will hold up momentarily and then its spring r^{38} will drop back and open the branch release circuit just described at the spring and front contact r^{35} . The release magnet R^1 will thus be energized and deenergized thus releasing the connector switch. This energizing and deenergizing of the release magnet of the intermediate finder switch F^1 as before described will cause the release of the other switches as previously set forth.

I have heretofore stated that the distributor switches D and D^1 need not be considered in following the operation in putting through a call as this distributor switch is only required where several finders in multiple are used, but a brief description thereof is as follows: The starter wires 19^a or 51^a are connected to terminal contacts engaged by the wiper d^1 and the starter wire (19 or 51) is connected to wiper d^1 through wire d^2 , contact d^3 , spring d^4 , wire d^5 . The switch being in its normal position, wiper d^1 rests on the terminal contact of the next idle finder switch and a starting impulse would pass right through the switch by the circuit just described including wiper d^1 to the starter wire 19^a or 51^a as the case may be. Means are provided for advancing the wiper d^1 , (as soon as the proper finder has been set into operation), to the terminal of the next idle finder. The starter wire (19 or 51) which enters this switch is branched at d^6 , one branch leading to the motor magnet d^7 thence by wire d^8 , contact d^9 , spring d^{10} , wire d^{11} , back contact d^{12} , spring d^{13} , wire d^{14} , battery and ground so

that the impulse which passes through the distributor switch to start the idle finder also starts the motor magnet d^7 , of the distributor. This motor magnet d^7 energizes 5 and attracts spring d^{15} , against contact d^{16} which is connected by wire d^{17} to relay d^{18} , and thence by wire d^{11} , contact d^{12} , spring d^{13} , wire d^{14} , to battery and ground. The first movement of the motor magnet also 10 energizes the relay d^{18} which in turn breaks the circuit of the motor magnet at contact d^9 . That causes the motor magnet to release and the switch wiper d^1 is advanced to the next contact and this continues to operate 15 until the ground at the line relay or in the switch S , which gave the starting impulse, has been removed by the finder switch finding the line or the trunk to which a line has become connected. In the case 20 of the line finder this would occur at the time the cut-off relay is operated and allows the line relay to drop back and in the case of the intermediate finder or back test it will occur when the relay S^6 is operated to 25 open the ground circuit at contact 81, in the selector switch. When the distributor wiper d^1 has passed over all the terminals, the wiper d^{20} engages grounded contact d^{21} , this wiper d^{20} is connected by wire d^{22} to release 30 magnet d^{23} thence by wire d^{24} , contact d^{12} , spring d^{13} , wire d^{14} and battery to ground. This operates the release magnet d^{23} which 35 closes the circuit of the release relay d^{28} at contact d^{25} as follows: grounded spring d^{26} contact d^{25} , wire d^{27} , relay d^{28} , wire d^{14} to battery and ground. This energizes the release relay d^{28} which breaks the contact for the release magnet and the energizing 40 and deenergizing of the release magnet d^{23} causes the switch to be released and return to normal. The relay d^{28} also holds open the circuit of the wiper d^1 and while it is 45 returning to normal position the relay d^{28} , being slow, gives this a time interval for the switch to return to normal.

Having thus described my invention, I claim:

1. An automatic telephone system comprising a plurality of selector switches and 50 a connector switch, a finder switch associated with each of said selector switches and said connector switch, releasing devices in said switches, a release circuit extending between said switches, means to release the

connector switch and its associated finder 55 switch, and means to successively release in pairs each of said selector switches and its associated finder switch when the preceding switch and its associated finder is released.

2. An automatic telephone system, comprising a plurality of selector switches and a connector switch, a finder switch associated with each of said selector switches and said connector switch, releasing devices 60 in said switches, a release circuit extending between said switches, a bridged line relay associated with said connector switch which controls the release of said connector and its associated finder switch, the release of 65 each finder switch controlling the release of 70 the succeeding switch and its associated finder switch.

3. In an automatic telephone system, a connector switch and a finder switch, a release magnet in said connector switch, a 75 bridged line relay controlling the operation of said release magnet, a release magnet associated with said finder switch controlled by the operation of the release magnet of the connector switch, a relay associated with the finder switch controlled by the release magnet in the finder switch, said relay controlling the joint deenergization of said release magnets to release said switches. 80

4. In an automatic telephone system, a selector and a connector switch, a finder switch associated with each of said switches, a release magnet for each of said switches, a bridged line relay controlling the actuation 85 of said connector release magnet, said connector release magnet controlling the actuation of the finder release magnet, and a relay associated with said finder switch which is operated by the actuation of the finder release magnet and which controls the simultaneous deenergization of said release magnets to release the connector and its associated finder switch and a circuit established 90 by the release of said finder switch to cause the joint release of the selector and its associated finder switch. 95

In testimony whereof, I have hereunto set my hand this 31st day of May, 1912.

CHARLES L. GOODRUM.
